UNITED STATES PATENT OFFICE.

JOHN H. LOUCH, OF LITHIA SPRINGS, GEORGIA.

DESIGN FOR A LIQUID CONTAINER OR VESSEL.

SPECIFICATION forming part of Design No. 33,130, dated August 28, 1900.

Application filed June 28, 1900. Serial No. 22,000. Term of patent 14 years.

To all whom it may concern:

Be it known that I, JOHN H. LOUCH, a citizen of the United States, residing at Lithia Springs, in the county of Douglas and State of Georgia, have invented and produced a certain new and original Design for Liquid-Containers; and I do declare the following to be a full, clear, and exact description of the invention, such as will enable others skilled in the art to which it appertains to make and use the same.

My invention relates to a design for a new and useful article of manufacture—a liquid container or vessel.

The design consists of the features hereinafter fully described and claimed and is shown in the accompanying drawings, in which—

Figure 1 is a side view of the liquid container or vessel embodying my design. Fig. 2 is a top plan view of the same, and Fig. 3 is a front end view looking toward the spout or nozzle of the container.

The leading features of the design reside in a body of approved form having a neck

extending approximately in the plane of one 25 of its sides, a tapering spout extending longitudinally from the neck and having at its inner end a collar and adjacent to its outer end a boss and tubular pendent projection.

1 in the drawings represents the body of 30 the liquid container or vessel, having a neck 2 projecting longitudinally in the plane of one side thereof. From this neck extends a tapering spout or nozzle 3, formed by providing at its inner end a collar 4 and adjacent 35 to its outer end an approximately-annular boss 5 and a tubular pendent projection 6.

Having thus described my invention, what I claim is—

The design for a liquid container or vessel 40 substantially as herein shown and described.

In testimony whereof I have hereunto set my hand in presence of two subscribing witnesses.

JOHN H. LOUCH.
